UNITED STATES PATENT OFFICE

BYERS W. KADEL, OF BALTIMORE, MARYLAND, ASSIGNOR TO THE GOULD COUPLER COMPANY, OF NEW YORK, N. Y., A CORPORATION OF MARYLAND

TRUCK

Application filed December 11, 1928. Serial No. 325,246.

This invention relates to trucks for railway rolling stock and particularly to such trucks which may be readily taken down or disassembled to facilitate the repair or replacement of the parts.

The principal object of my invention, generally considered, is to provide trucks for railway rolling stock in which the bolsters are preferably formed with only inner guide lugs, thereby facilitating assembly and disconnection with respect to the associated side frames while still assembled with the associated spring plank and bolster springs, the brake hangers being supported on transverse rods fitting in registering apertures or pockets in the frames, whereby they do not interfere with the quick removal of the frames.

Another object of my invention is to provide a quick take down truck in which the spring plank interlocks with the associated side frames and supports bolster springs and an associated bolster which is freely insertable and removable from between the guide columns, the brake hangers being supported on transverse rods freely fitting at their ends in corresponding apertures or pockets in the frames, whereby said frames are readily removed upon lateral outward movement thereof after disconnection from the spring plank.

A further object of my invention is to provide brake hanger supporting rods which freely fit at their ends in the associated side frames, being held in position either by the ends thereof engaging portions of said frames or locked by quickly detachable means, such as keys or cotters, said brake hangers being mounted in proper position thereon by corresponding means.

A still further object of my invention is to facilitate the taking down of trucks, whereby the side frames thereof may be removed upon the mere dropping of the wheels, the relative lowering of the frames to disconnect them from the spring plank and the outward movement thereof to withdraw them from the spring plank, bolster, bolster springs, and brake hanger supporting rods extending between and supported by the side frames.

Other objects and advantages of the invention relating to the particular arrangement and construction of the various parts will become apparent as the description proceeds.

Referring to the drawings illustrating my invention, the scope whereof is defined by the appended claims.

Figure 1 is a fragmentary side elevation of a truck showing the intermediate portion of a side frame and associated parts, the journal boxes and associated journals and wheels being of ordinary construction and not illustrated.

Figure 2 is a transverse section on the line 2—2 of Figure 1, the bolster, spring plank and springs being omitted.

Figure 3 is a horizontal sectional view on the line 3—3 of Figure 1, looking in the direction of the arrows.

Figure 4 is a horizontal sectional view corresponding to Figure 3, but showing a modification.

Referring to the drawings in detail, like parts being designated by like reference characters, and first considering the embodiment of my invention illustrated in Figures 1, 2 and 3, a fragmentary portion of a truck is shown comprising a side frame 1 having a compression member 2, tension member 3, and bolster guide columns 4 spacing intermediate portions of said compression and tension members, leaving a window opening 5 therebetween. As is usual, the compression and tension members extend outwardly and unite at their ends at which are either formed integral journal boxes (not shown) or said ends are adapted to connect with journal boxes, in which are received journals of the car axles upon which are mounted the supporting wheels.

The side frame illustrated is of the cast type shown in the patent to Donald S. Barrows, 1,652,808, dated December 13, 1927, but if desired, any type of frame may be employed. The type of frame illustrated has auxiliary tension or reinforcing portions 6 which close the lower corners of the window opening 5, and the associated spring plank 7 supported on the tension member between the guide columns is formed with corresponding

corrugations 8 which interlock with the reinforcement 6 and hold the plank in proper relation with respect to each frame. If an ordinary side frame is used with the usual lugs, the spring plank, of course, will be formed with corresponding apertures interlocking with said lugs, so that in any event, the spring plank preferably serves to hold the frames in proper relation with respect to one another, but is readily disconnected therefrom by either raising the spring plank or dropping the frames with respect thereto.

Supported on the spring plank 7, with or without the usual spring plates, are bolster springs 9, said springs being preferably standard G springs and the number of said springs corresponding with the capacity of the truck. Supported by means of said springs 9, with or without the usual top spring plates, is a bolster 10 which is preferably formed with inner guide lugs 11 only, the usual outer guide lugs being omitted to facilitate assembly and removal of the side frames with respect to the other portions of the bolster.

Extending between the side frames are means for supporting the brake hangers 12, said means preferably comprising a pair of rods or bars 13 with their ends fitting into registering apertures 14 in the side frames 1 and held against undesired lateral movement after the frames are assembled by engagement of the ends thereof with some portion of the frame, for example, the outer flanges 15 of the bolster guide columns 4. In order to increase the supporting area for the ends of the rods 13 inwardly extending bosses 16 are provided in which the apertures 14 are formed. The brake hangers 12 may be of generally normal construction with eyes 17 at their upper ends through which are threaded the supporting rods 13. Outward movement of the hangers 13 is prevented by the bosses 16, and inward movement may be prevented by collars or washers 18 on the rods, said washers, if used, being held in position in any desired manner as by means of cotters or keys 19.

Referring now to the embodiment of my invention illustrated in Figure 4, a construction is there disclosed involving a side frame 1^a, a bolster 10^a, and other associated parts identical with that of the previous embodiment, except that the outer flanges 15^a of the bolster guide columns 4^a are perforated to correspond with the apertures 14^a, and the brake hanger supporting rods 13^a are extended through said perforations 20 and locked in place outside of the frames as by means of washers 21 and flat split keys or cotters 22. Such construction acts to supplement the effect of the spring plank in locking the frames in proper position with respect to one another, although it slightly complicates the connection between the frames and slightly

increases the time of assembly or taking down the parts of the truck.

From the foregoing disclosure, it will be apparent that I have devised a quick take down truck in which the side frames may be quickly removed by merely dropping or otherwise disconnecting the wheels and axles therefrom, lowering the frames relative to the spring plank to disconnect them from said spring plank and moving said frames laterally outward to withdraw them from the ends of the bolster, spring plank, and brake hanger supporting means without the necessity of disarranging the assembly of the spring plank, bolster, and bolster springs, and without any complicated operations in disconnecting the frames from the associated brake rigging. Modifications may be made within the spirit and scope of the appended claims.

Having now described my invention, I claim:

1. A truck for railway rolling stock comprising a pair of side frames, a spring plank supported thereon and extending therebetween, bolster springs supported by said spring plank, a bolster supported by said springs, rods extending from side frame to side frame and supported at their ends thereby, and brake hangers supported on said rods.

2. A truck for railway rolling stock comprising a pair of side frames, a spring plank extending therebetween and interlocked at its ends with said frames, bolster springs supported by said spring plank, a bolster supported by said springs and formed with inner guide lugs only engaging the bolster guide columns of the frames, and brake hanger supporting rods extending between the side frames with their ends fitting in pockets therein, whereby the side frames may be removed upon disconnecting the spring plank therefrom.

3. A truck for railway rolling stock comprising a pair of side frames, a spring plank supported thereon with its ends interlocked with said frame, bolster springs supported by the ends of said spring plank, a bolster supported by said springs and formed without the usual outer guide lugs, and means for supporting associated brake hangers extending between the side frames with the ends freely fitting in corresponding pockets in said frames, whereby neither the bolster nor the brake hanger supporting means interfere with the free and quick removal of the side frames from the truck.

4. A truck for railway rolling stock comprising a pair of side frames, a spring plank supported thereon and extending therebetween, a nest of springs supported on each end of said spring plank, a bolster supported at its ends on said nests of springs, said bolster being freely insertable and removable with respect to the frames, rods ex-

tending between said frames and fitting in registering apertures therein, means for maintaining said rods in position with respect to said frames, and brake hangers supported on said rods.

5. In a truck, in combination with the side frames thereof, unitary means for supporting a pair of brake hangers from said frames comprising a rod extending transversely of the truck.

10. 6. In a truck, in combination, a pair of side frames, brake hanger supporting rods extending from one frame to the other and freely fitting in registering apertures therein, and means for maintaining said rods in position while not preventing the quick removal of said frames from the truck.

15. 7. A quick take down truck comprising a pair of side frames, a spring plank, bolster springs, a supported bolster without outer guide lugs, and brake hanger supporting means extending between said frames and freely fitting therein, whereby said truck may be taken down upon a disconnection of the spring plank from the side frames without disturbing the relation between the bolster, spring plank and springs upon moving said frames laterally to release them from the brake hanger supporting means.

20. 8. In a truck, in combination, brake hangers, and rods supporting said hangers extending between the side frames and releasable therefrom upon outward lateral motion of said frames.

25. 9. The method of taking down a truck comprising dropping the wheels, lowering the frames to disengage the spring plank therefrom, and moving the side frames laterally to release them from brake hanger supporting rods.

30. 10. In a railway truck, a pair of side frames, each frame comprising inner and outer flange portions, and rods adapted to support brake hangers extending between said frames and passing through registering apertures in the adjacent flange portions thereof and prevented from undesired removal by the outer flange portions thereof.

35. 11. In a railway truck, in combination, a pair of side frames and rods extending between said frames and adapted to support brake hangers and extending through registering apertures in said frames, the ends of said rods extending beyond the outer surfaces of said frames, and retainer means connected thereto for preventing undesired removal.

In testimony whereof I affix my signature.
